UNITED STATES PATENT OFFICE.

LEWIS W. GILBERT, OF SENECA FALLS, NEW YORK.

AUTOMATIC SWITCH.

Application filed January 19, 1924. Serial No. 687,322.

The object of this invention is to provide and 13 with a commercial type of starting particular means for completing a circuit switch 14. Wire 15 leads to a source of current through the starting motor of an internal combustion engine.

5 A further object is to provide for automatically completing this circuit when the engine stalls.

A still further object is to provide an 10 automatic switch to be mounted on the usual starting switch, and a circuit closing device connected with the intake manifold, and acting to complete a circuit through the automatic switch when starting the engine, but 15 automatically opening this circuit and the motor circuit when the engine is running,— the movement to open position being due to suction in the intake manifold.

Another object is to avoid the danger of 20 unduly taxing the battery by leaving the ignition switch closed when the car is at rest, sufficient noise being made in turning over 25 the motor to attract the driver's attention.

With the foregoing and other objects in view, the invention consists in the novel construction and arrangement of elements described, illustrated and claimed, it being understood that modifications may be made within the scope of the claim without departing from the spirit of the invention.

30 In the drawings forming part of this application,

Figure 1 is a diagrammatic view showing the position of certain of the elements of this attachment, with reference to the starting switch of a standard type.

Figure 2 is a view in section thru the mounting means of magnet 30, and showing in elevation and section the contact elements thru which a circuit is to be completed when 40 this magnet is energized.

Figure 3 is a view looking from the lower side of Figure 2.

Figure 4 is a view in vertical section thru the housing of a plunger which acts by gravity 45 to close a pair of contacts when the engine stalls, the plunger otherwise being lifted for breaking the circuit at this point, by suction in the intake manifold with which the housing or cylinder for this plunger is 50 to be connected.

Figure 5 is a diagrammatic view of the circuits and elements connected therewith, the structure of Figure 4 being illustrated conventionally in the lower part of Figure 5.

55 In carrying out the invention, I employ brackets 10, 11, which are connected at 12

A resilient arm 18 is in electrical connection with bracket 10 by means of bolt 19, and carries a copper contact 20 normally spaced from a similar contact 21 carried by element or bolt 22, the latter being in electrical connection with bracket 11. 60 65

Strips 23, 24 of insulation are positioned on opposite sides of a supporting element 26, and in the location shown with reference to brackets 10 and 11, arm 18, and bolt 22.

A screw 27 passes through the strips 23, 70 24, into core 28 surrounded by coil 30. This coil is in the circuit including wire 31 from switch S and including wire 33 leading to terminal 34 and contact 35 mounted in and insulated from the device to be connected 75 with the intake manifold.

This device last named is responsive to suction in the intake manifold, and includes a cylinder 37 having a port 38 and a threaded elbow connection 39 provided with 80 a bore 40 through which communication is established with the manifold.

The plunger 41 in the cylinder carries a contact member 42 cooperating with contact 35, and mounted on the plunger is a ball 85 valve 43 closing port 44 and bore 40, when the plunger rises, because of suction in the intake manifold. Contacts 35, 42 are closed by gravity, and contact 42 is grounded through the plunger, the cylinder and the mounting thereof.

Battery current passes thru wire B, thru switch S, to wire I connected with the ignition system. When the ignition switch is first closed, current passes through wire 31, coil 30, wire 33, terminal 34, contacts 35, 42, plunger 41, cylinder 37, to ground. Core 28 being energized, arm or armature 18 is lifted, and closes contacts 20, 21, so that a circuit is completed through wire 15, bracket 10, bolt 19, arm 18, contacts 20, 21, bolt 22, bracket 11, wire 16, and the starting motor 17.

After the engine starts the suction in the intake manifold, and in bore 40 of elbow connection 39, lifts plunger 41 and breaks contact between 35 and 42, thereby deenergizing core 28 and opening contacts 20, 21 in the circuit of the starting motor. As long as suction is maintained, there will be no further change in the circuits here de-

scribed, but if the engine stalls because of careless driving, the lack of suction will cause plunger 41 to drop and make contact at 35, 42, resulting in repeating the operation before outlined.

Port 38 allows air to enter at cranking speeds without raising the plunger, and the ball valve 43 when closed prevents leakage of air into the manifold.

10 What I claim is:

In a device of the class described, a circuit including a source of current, a starting motor in the circuit, electrically operated means for closing the circuit, said means including a second circuit, means responsive to suction for opening the second

circuit, said means last named including a cylinder and a plunger, contact members carried respectively by the plunger and by the lower end of the cylinder, the cylinder being mounted vertically, and the upper end of the cylinder including a tubular connection for establishing communication with an air intake manifold of an engine, and a valve carried by the plunger for closing said tubular connection when the plunger responds to suction and separates the contact members, the cylinder having a port admitting air above the plunger when the latter is not under the influence of suction. 30

In testimony whereof I affix my signature.

LEWIS W. GILBERT.
